TOILET TISSUE DISPENSER

Silvio Sarro, Brooklyn, N.Y.

Application January 29, 1958, Serial No. 49,440

Term of patent 14 years

(Cl. D4—3)

Fig. 1 is a front elevational view of a toilet tissue dispenser, showing my new design;

Fig. 2 is a side elevational view of the same;

Fig. 3 is a similar view to Fig. 1 showing the hinged lid in open position;

Fig. 4 is a bottom plan view in open position; and

Fig. 5 is a vertical sectional view taken on the line 5—5 of Fig. 3.

I claim:

The ornamental design for a toilet tissue dispenser, substantially as shown.
